DOOR LOCK

Frank J. McConnell, New Britain, Conn., assignor to The American Hardware Corporation, New Britain, Conn., a corporation of Connecticut

Application June 6, 1955, Serial No. 513,483

4 Claims. (Cl. 292—169)

This invention relates to a door lock and more particularly to a door lock of the cylindrical type, and constitutes an improvement over the cylindrical door lock structure shown in my prior application, Serial No. 312,290, filed September 30, 1953, and now abandoned.

The instant invention is embodied in the dogging mechanism of a cylindrical door lock which includes the basic operating unit disclosed in the co-pending application of Frank J. McConnell et al., Serial No. 508,018, filed May 13, 1955; and which mechanism renders the lock particularly adapted for bedroom or bathroom doors. It will be understood, however, that the dogging mechanism disclosed herein can readily be used in other types of cylindrical door locks without departing from the scope of this invention.

The primary object of this invention is to provide an inexpensive dogging mechanism which is particularly adapted for use in the operating unit disclosed in said co-pending application.

A further object of the present invention is to provide a dogging bar for such a cylindrical lock having novel means thereon cooperating with means on the retractor of the lock for retaining the dogging bar in dogging position.

A still further object of the invention is to provide such a dogging bar which is released from dogging position when the retractor is moved to its retracted position by operation of the inner door knob or by the latch bolt as it is depressed upon engagement with the strike.

More specifically, this invention is embodied in a flat dogging bar which carries a spring clip that is adapted to engage a pin on the retractor of the operating unit to retain the dogging bar in dogging position.

Additional objects and advantages of this invention will be more clearly understood from the following description and the accompanying drawings in which:

Fig. 1 is a plan view of my improved door lock, partially in central horizontal section, illustrating the dogging means in normal undogging position.

Fig. 2 is a front view thereof, partially in vertical section, further illustrating the construction of the dogging means.

Fig. 3 is a sectional end view of the lock with the outer rose removed.

Fig. 4 is a sectional end view of the lock taken substantially on line 4—4 of Fig. 1.

Fig. 5 is a view similar to Fig. 1, but illustrating the dogging mechanism in dogging position.

Fig. 6 is an enlarged fragmentary front view illustrating a portion of the dogging bar and of the retractor of the lock and the spring clip which retains the dogging bar in dogging position.

Fig. 7 is a fragmentary end view thereof taken on line 7—7 of Fig. 6.

Fig. 8 is a similar view taken on line 8—8 of Fig. 6.

The cylindrical door lock disclosed herein is particularly adapted for use on bathroom and bedroom doors wherein it is usually required that means be provided for dogging the outer knob of the lock against operation

2

from the outer side of the door; said dogging means being automatically released when the inner knob is rotated, or, in the event that the dogging means had inadvertently been moved to dogging position while the door is open, 5 upon depression of the retractor by the latch bolt as it engages the strike. In such locks, it is also usually necessary to provide means whereby the dogging mechanism may be released from the outer side of the door should the person in the room be incapable of unlocking the door 10 due to accident or illness.

It will be noted from the accompanying drawings that, with the exception of slight modifications and the inclusion of the dogging mechanism, the door latch operating unit disclosed therein is the same as that disclosed in the 15 above mentioned co-pending application Serial No. 508,018. However, in order to permit a clear understanding of the operation of the dogging mechanism embodying the instant invention, the entire mechanism will be described herein.

20 The cylindrical door lock illustrated in Fig. 1 of the drawings consists of an operating unit 5 and a latch unit 6 which are mounted on a door 7 in the conventional manner; said operating unit being received in a hole 8 bored through the face of the door, and the latch unit 25 being received in a hole 9 bored into the edge of the door at right angles to and intersecting the hole 8. The latch unit is attached to the operating unit in a conventional manner which will be hereinafter described.

The operating unit 5 of the door lock comprises a 30 cylindrical cup-shaped casing 10 which houses and supports the operating mechanism and is provided at its inner end with an integral end wall 11 having a centrally located circular opening 12 therethrough, and at its opposite open end with prongs 13 which project longitudinally therefrom. The wall of the casing contains the conventional rectangular opening 10-a therethrough to the opposite edge portions of which the conventional fingers extending from the latch unit are attached in the usual manner as shown in Fig. 4. A cover plate 14 is secured 35 to the outer open end of the casing 10 by the prongs 13 which project through aligned slots 15 in said cover plate and are peened over its outer surface to thereby firmly secure the plate against the end of the casing. The said cover plate has a centrally disposed opening 16 therethrough which is disposed coaxially with respect to the opening 12 in the end wall 11.

The casing contains a U-shaped retractor guide including a transversely curved base portion 17 from the upper and lower edges of which project centrally disposed parallel arms 18—18. The said retractor guide is disposed within the casing 10 with its base 17 resting against the cylindrical wall at the rear of the casing and its arms 18—18 extending forwardly towards the opening 10-a and lying equidistant from the longitudinal axis of the lock; said base portion being secured between the end wall 11 and the cover plate 14 in the manner clearly disclosed in said co-pending application Serial No. 508,018. The free ends of said arms 18—18 are disposed in slots 50 in a guide plate 19 that extends across the casing adjacent the opening 10-a and is secured between the end wall 11 and the cover plate 14 as also clearly disclosed in said co-pending application; said guide plate having an opening therethrough disposed centrally between said arms.

60 The retractor guide means above described slidably support a retractor 20 including a base in the form of a flat plate 21 having stiffening flanges 22—22 extending perpendicularly from its upper and lower edges. The plate 21 contains centrally located slots 23—23 adjacent each of the flanges 22—22 which receive the arms 18—18 of the retractor guide upon which said plate, 65 forming the rear end of the retractor, is slidably sup-

ported. A reinforcing plate 24 is disposed against the rear surface of the plate 21 and a centrally located notch 25 extends into both plates from their outer edges. For the purpose of the instant invention, a pin 26 is secured to the base of the retractor and projects perpendicularly therefrom adjacent its inner edge and the axis of said pin intersects the axis of the lock. Spaced latch bolt retracting fingers 27-27 extend perpendicularly from the plate 21 equi-distant from said axes and are secured to said plate by lugs which project through the plates 21 and 24 and are bent upwardly therebehind, as illustrated in Fig. 4, to secure the said plates together and the fingers to said plates. Said fingers extend through and are guided in the opening in the guide plate 19, which provides a support for the forward end of the retractor, and also extend through the opening 10-a in the wall of the casing. The outer ends of said fingers are bent inwardly, in the conventional manner, to permit engagement thereof with the conventional retractor bar 28 which extends from the latch unit 6. It will be noted from Fig. 4 that the ends of the retractor fingers 27-27 are received in notches 29-29 in the retractor bar 28 so that when the latch bolt 6-a, extending from the latch unit, is depressed, as by engagement with the strike, the retractor will move rearwardly in unison therewith. The retractor is urged into its normal projected position by a spring 30 which is disposed between the base 17 of the retractor guide and the plate 24 of the retractor, as clearly illustrated in Figs. 1 and 4.

The retractor actuating means carried at the inner and the outer sides of the casing of the door lock are the same as previously disclosed in my co-pending application Serial No. 312,291, filed September 30, 1952, and now Patent No. 2,759,750, issued August 21, 1956. Said actuating means include elongated tubular bushings 31-31 which are rotatably contained in the openings 12 and 16 in the end wall 11 and the cover plate 14. Each of said bushings is provided with radially extending flanges 32-32 and a projection 33 which engage the surface adjacent the hole in which the bushing is mounted and prevent axial movement thereof outwardly of the casing. Each of said bushings also has a segmental rollback portion 34 which extends into the casing and whose opposite edges engage the plate 21 of the retractor and limit outward movement thereof to its normal position under the influence of the spring 30. The bushings 31-31 each contain a plurality of equally spaced slots 35 which extend thereinto substantially to the plane of the outer surface of the member in which the bushing is mounted and said slots receive similarly disposed lugs 36 on a retaining washer 37 which surrounds each of the bushings and abuts the outer surface of the member in which the bushing is mounted. The lugs 36 project through the slots 35 and into the bore of the bushing wherein they are engaged by the end of a tubular spindle, 38 and 39, respectively, which is telescopically received in the bore of its respective bushing and is secured therein with its inner end abutting the lugs 36 by being soldered, spot-welded, or otherwise fastened to the bushing. The outer tubular spindle 39 and its associated bushing 31 and retaining washer 37 contain aligned slots 41, 42 and 43, respectively, which are normally aligned with a slot 44 in the cover plate 14 extending radially from the opening 16 therein. The inner spindle, retaining washer and bushing also contain similar slots since they are the same parts that are used on the outer side of the lock, but said slots do not cooperate in any way with the dogging mechanism of the present invention.

The tubular spindles 38 and 39 carry inner and outer knobs 45 and 46, respectively, each of which has a shank portion which telescopically receives its respective spindle. The outer knob is permanently fastened to the outer spindle while the inner knob is detachably secured to its spindle by a depressible knob catch. It will

be understood that, when rotated, either of said knobs will rotate its respective bushing 31 through the tubular spindle to which it is secured and will urge the retractor rearwardly against the spring 30 to thereby retract the latch bolt 6-a.

The cover plate 14 has a decorative rose 47 permanently secured thereto and said rose projects outwardly from said cover plate to conceal the slots 41, 42, 43 and 44, as clearly illustrated in Fig. 1.

10 A clamping plate 48 of conventional form is provided on the inner side of the lock and said plate is adjustable relatively to the outer cover plate 14 to permit installation of the lock on doors of different thicknesses. The operating unit is secured to a door by screws 49-49

15 which extend through holes in the clamping plate 48 and are threaded into holes in the casing 10. A rose 50, similar to the rose 47, is detachably secured to the clamping plate 48 to provide the required decorative trim on the inner side of the lock.

20 The dogging means incorporated in the above described operating unit for selectively dogging the outer knob against rotation comprise a one-piece dogging bar 51 which includes an outer section 51-a to the end of which is secured a conventional pushbutton 52 that extends through

25 an opening 53 in the wall of the inner knob. The outer section 51-a of said dogging bar is slidably supported axially of the inner tubular spindle by a disk 54 which is contained within said inner spindle and is positioned by oppositely disposed ears 55-55 extending radially inwardly from the wall thereof; said disk being retained against said ears, and the dogging bar being retained in its normal undogging or projected position illustrated in Fig. 1, by means of a compression spring 56 which is disposed between said disk and the base 52-a of the pushbutton.

30 The intermediate section of the dogging bar 51 contains a first offset portion 51-b which extends from the outer section of the bar and is disposed forwardly of and substantially parallel thereto and has oppositely disposed wings 57-57 extending therefrom for a purpose to be hereinafter described. The intermediate section of said dogging bar contains a second forwardly offset portion 51-c that extends parallel to the previously described portions of the bar and over the plate 21 of the retractor 35 between the retractor fingers 27-27. It will be noted from Fig. 1 that the rear surface of this portion of the dogging bar is spaced from the surface of the plate 21 of the retractor over which it extends, and that said portion 51-c contains a longitudinal slot 59 through which the pin 26 projects. The inner section 51-d of said bar is offset rearwardly relatively to the intermediate portion 51-c thereof and extends closely adjacent the plate 21 of the retractor and into the outer spindle 39. An integral supporting ear 60 is bent perpendicularly from the bar and said ear slidably supports the outer end of the dogging bar in the inner tubular spindle. It will be understood that said ear also prevents lateral movement of the inner end of the dogging bar. A blade 61 is secured to the dogging bar adjacent its inner end and projects perpendicularly therefrom in the plane of the axis of the unit and toward the rear of the casing. The blade is fastened to the dogging bar by a lug 62 which projects through a slot in said bar and is peened over the edge of said slot.

35 The edge of said blade adjacent the retractor passes through the slot 25 therein and said blade is provided with a finger portion 63 that is disposed in alignment with the slots 41, 42, 43 and 44. The said dogging bar is prevented from turning relatively to the operating unit by means of an extension 64 which extends from the finger 63 on the blade 61 into a slot 65 in the base portion 17 of the retractor guide. The blade is rigidly supported relatively to the dogging bar by a lug 66 which extends into a slot 67 in the ear 60, as illustrated in Figs. 1 and 3.

40 The dogging bar carries a spring clip 68 which coop-

45

50

55

60

65

70

erates with the pin 26 for yieldingly retaining said bar in dogging position. This spring clip is U-shaped in form and has leg portions 68-a—68-a extending from a resilient bight portion 68-b which is disposed against the forward surface of the portion 51-b of the dogging bar and against the wings 57—57. The bight portion is disposed between a positioning lug 69, which is formed on the dogging bar to properly locate the spring clip thereon, and a tab 70 which is bent from the bar and over the bight portion; said tab also securing the spring clip to the bar. The spring clip is disposed centrally of the bar and its legs extend from the bight portion toward the outer side of the lock in substantially parallel relation beyond the sides of the dogging bar and converge behind the portion 51-c thereof. Said legs are bent to provide oppositely disposed humps 71—71 which lie equi-distant from the center of the dogging bar and extend under the slot 59 therein outwardly of its inner end, said humps being normally spaced apart a distance less than the diameter of the pin 26 to form a restricted passage therebetween as illustrated in Fig. 2. Said legs then diverge from the hump portions 71—71 and are provided with parallel extensions 72—72 which extend beyond the pin 26 and on the opposite sides thereof.

The dogging bar is urged into its projected or undogging position by the compression spring 56, its movement to this position being limited by the engagement of the extension 64 on the blade 61 with the end of the slot 65. When the dogging bar is in its undogging position, the humps 71—71 on the spring clip are disposed outwardly of the pin 26 and the extensions 72—72 lie at the opposite sides of the pin and prevent movement of the spring clip out of alignment with the pin should the tab 70 fail to properly hold the spring clip.

It will be understood that when in its undogging position, the dogging bar will not interfere with the normal operation of the lock. The retractor can be retracted by rotation of the inner or the outer knob in either direction and as said retractor moves rearwardly, the pin will move out of the slot 59. Since the bar is located in its undogging position by engagement of the extension 64 with the end of the slot 65, said slot 59 in the dogging bar will always remain in alignment with the pin 26 and will receive said pin upon return of the retractor to its normal position.

When it is desired to dog the outer operating knob against operation, it is only necessary to depress the pushbutton. This will move the entire dogging bar 51 against the spring 56 and relatively to the pin 26 on the retractor and urge the dogging finger portion 63 on the blade 61 toward the notches 41, 42, 43 and 44. As the humps 71—71 on the spring clip 68 engage the rounded surface of the pin 26, they will ride upwardly on said surface and the legs of the spring will move apart, and as the humps move past the pin, the legs of the spring will be urged together. When the outer end of the slot 59 in the dogging bar engages the pin 26, further movement of the dogging bar and pushbutton is prevented and the dogging bar is in dogging position as illustrated in Fig. 6. The humps are then disposed against the inner side of the pin and in engagement with its surface and thereby retain the dogging bar in dogging position against the force of the spring 56. When in dogging position, the dogging finger 63 will be disposed in the slots 42, 43 and 44 and will thereby prevent rotation of the outer tubular bushing 31 and consequently of the outer knob 46.

It will be understood that the inner knob is still free to rotate to permit operation of the lock from the inner side of the door and, when the retractor is urged rearwardly upon operation of the inner knob, the pin 26 will be carried rearwardly therewith and out of engagement with the humps 71—71 on the spring clip 68, which will release the dogging bar and permit the spring 56 to return said bar to its normal undogging position. It will also be

understood that if the dogging bar has been inadvertently moved into dogging position while the door is open, the depression of the latch bolt on engagement with the strike when the door is closed will cause rearward movement of the retractor which releases the dogging bar in the same manner as above described to prevent accidental locking of the door.

If the person in the room has locked the door and is unable to unlock it due to illness or accident, the dogging bar may be released by inserting a suitable tool, such as a nail or a screw-driver, indicated at 73, through a centrally disposed hole 74 in the outer knob and into engagement with the ear 60 on the end of the dogging bar and then pushing said bar inwardly to force the humps 71—71 back over the pin 26 and thereby permit return of the dogging bar to undogging position to permit operation of the outer knob for opening the door.

The latch operating unit is supplied as a pre-assembled mechanism and to install it in a door, having the required holes 8 and 9 bored therein, requires only the removal of the inner knob 45, the inner rose 50 and the clamping plate 48. The latch unit is first inserted into the hole 9 and is secured therein in the normal manner. The operating unit is then inserted into the hole 8 from the outer side of the door with the ends of the retractor fingers in position to enter the notches in the retractor bar 28 extending from the latch unit. The operating unit is moved through the hole until the cover plate 14 abuts the outer surface of the door. The inner clamping plate 30 is then placed in position against the inner surface of the door and the screws 49—49 are threaded into the casing 10 and, when tightened, securely clamp the operating unit to the door. The inner rose 50 is then attached to the clamping plate and the inner knob is placed on the inner spindle to complete the installation.

It will be understood from the above description that my invention provides an inexpensive and durable door lock having a dogging mechanism which is simple in operation, economical to produce and does not require complicated or numerous parts for its support or operation.

I claim:

1. A door lock comprising a casing, a retractor in said casing, a latch bolt adapted to be retracted by said retractor, inner and outer independently operable operating members for actuating said retractor, a longitudinally movable dogging bar extending through said casing adjacent a portion of said retractor, dogging means controlled by said bar for dogging said outer operating member against operation, spring means normally biasing said dogging means out of dogging relation with said outer operating member, means accessible from the inner side of the lock for moving said dogging bar into dogging position, a projection on said retractor, a spring clip carried by said bar and including one or more portions adapted to resiliently engage said projection when said dogging bar is moved into dogging position and to retain said bar in dogging position against the biasing force of said spring means, and emergency access means on the outer side of said lock for permitting an inwardly directed force to be placed on said dogging bar to overcome the resilient holding force of said spring clip whereby said dogging bar will be moved out of dogging position.

2. A door lock comprising a casing, a retractor in said casing, a latch bolt adapted to be retracted by said retractor, inner and outer independently operable operating members for actuating said retractor, a longitudinally movable dogging bar extending through said casing, dogging means controlled by said bar for dogging the outer operating member against operation, spring means normally biasing said dogging means out of dogging relation with said outer operating member, means accessible from the inner side of the lock for moving said dogging bar into dogging position, a U-shaped spring clip carried by said dogging bar and including a resilient bight portion which

is secured to said bar and a pair of spaced forwardly extending legs, opposed portions of said legs extending into close proximity and providing a restricted passage therebetween, and a projection on said retractor normally aligned with said passage and adapted to be engaged by said opposed portions of the legs upon movement of said dogging bar into dogging position to retain said bar in said position against the biasing force of said spring means, and emergency access means on the outer side of said lock for permitting an inwardly directed force to be placed on said dogging bar to overcome the resilient holding force of said spring clip whereby said dogging bar will be moved out of dogging position.

3. A door lock comprising a casing, a retractor in said casing, a latch bolt adapted to be retracted by said retractor, inner and outer independently operable operating members for operating said retractor, a dogging bar extending through said casing adjacent a portion of said retractor and movable longitudinally into and out of dogging position, dogging means carried by said bar for dogging the outer operating member against operation, spring means normally biasing said dogging means out of dogging relation with said outer operating member, means accessible from the inner end of the lock for moving said dogging bar into dogging position, a pin projecting from said retractor through an elongated slot in said dogging bar, the inner end of said slot being engageable with said pin to limit movement of said bar to dogging position, a U-shaped spring clip having a resilient bight portion secured to said bar and spaced legs extending outwardly therefrom and disposed at opposite sides of said pins, said legs having opposed humps thereon providing a restricted passage therebetween and being disposed adjacent the inner end of said slot, and emergency access means on the outer side of said lock for permitting an inwardly directed force to be placed on said dogging bar to overcome the resilient holding force of said spring clip whereby said dogging bar will be moved out of dogging position.

4. A door lock comprising a casing, a retractor in said casing, a latch bolt adapted to be retracted by said retractor, inner and outer independently operable operating members for actuating said retractor, a dogging bar extending through said casing adjacent a portion of said retractor and being longitudinally movable into and out of dogging position, said bar having an elongated slot therein, a pin fastened to said retractor and projecting through said slot, the inner end of said slot being engageable with said pin to provide stop means for limiting movement of the bar to dogging position, spring means normally biasing said dogging means out of dogging relation with said outer operating member, means accessible from the inner side of the lock for moving said dogged bar into dogging position, resilient retaining means carried by said bar and engageable with said pin to retain the bar in dogging position against the biasing force of said spring means, said pin being disposed between said retaining means and the end of said slot when said bar is in dogging position and preventing longitudinal movement thereof, and emergency access means on the outer side of said lock for permitting an outwardly directed force to be placed on said dogging bar to overcome the resilient holding force of said resilient retaining means whereby said dogging bar will be moved out of dogging position.
